UNITED STATES PATENT OFFICE.

PHILIPP GELIUS, OF MUNICH, GERMANY.

PROCESS FOR THE PRODUCTION OF INSULATIONS AGAINST LOSS OF HEAT.

No Drawing.

Application filed September 17, 1921. Serial No. 501,448.

To all whom it may concern:

Be it known that I, PHILIPP GELIUS, a citizen of the German Republic, residing at Munich, Bavaria, Germany, have invented 5 certain new and useful Improvements in Processes for the Production of Insulations Against Loss of Heat, of which the following is a specification.

This invention relates to a process for the 10 production of insulations against loss of heat for accumulators for heat, for conduits, reservoirs and the like. The insulation is obtained with the aid of layers of wood shavings, straw, peat or other organic or vegetable substances adapted to be carbonized 15 which are coated with clay, cement or other convenient materials, said coating being applied before, during or after the mounting in place of said insulating-layers and serving for protecting the insulation.

By chemical binding, drying, heating or any other convenient treatment the envelope or mortar is transformed from the moist and soft state into the dry and solid state.

25 The layers enclosed in the envelope of mortar consist for instance of tissues, ropes or strings of wood shavings, wood fibres, straw, peat or other similar materials or substances which possess, owing to their structure a 30 high insulating capability and which are adapted to be carbonized, in order to increase essentially the degree of insulating capability. The complete carbonization of the insulating material is accelerated or produced and completed either mechanically, 35 for instance by direct burning with the aid of a blow-pipe-flame or the like or by means of incandescent bodies, chemically by caustic process, or finally electrically, in which case

40 thin wires would be embedded in the insulating material, said wires being wound so that they form electric resistances. When the ends of said wires are enclosed in an electric circuit the insulating materials are 45 carbonized. The carbonized substances are properly held by the protecting envelope of mortar.

According to the degree of the insulating effects which have to be produced the insulation can consist of one or of several layers 50 of insulating material. If several layers are used all these layers can be carbonized or only one or several of the same so that heat which radiates from the conduits, reservoirs or the like encounters first either the carbonized insulating materials which have a greater insulating action than the insulating substances in natural state, or the uncarbonized insulating materials, in which case the layer or layers of carbonized material 55 are farther distant from said objects.

I claim:

1. An improved process for the production of insulations against loss of heat consisting in covering the insulating mantle made from ropes of wood shavings with an envelope of mortar, the insulating capability of said wood shavings being increased by dry distillation.

2. An improved process for the production of insulations against loss of heat consisting in covering the insulating mantle made from ropes of wood shavings with an envelope of mortar, the insulating capability of said wood shavings being increased by 70 carbonization of the material effected with the aid of electric current.

3. An improved method for the production of insulations against loss of heat consisting in covering the objects to be insulated with a layer of combustible insulating material, e. g. wood shavings, straw, peat and like substances in convenient shape, in coating said layer with a mantle of mortar and in carbonizing said insulating material 75 80 in a convenient manner.

In testimony whereof I affix my signature in presence of two witnesses.

PHILIPP GELIUS.

Witnesses:

PAUL DREG,
RICHARD LUTZ.
